(57) **CLAIM**

The ornamental design for a floor mat, as shown and described.

DESCRIPTION

FIG. 1 is a front view of a floor mat, showing our new design;

FIGS. 2A and 2B together are a rear view thereof, it being understood that FIGS. 2A and 2B have been shown as separate figures for ease of illustration;

FIGS. 3A and 3B together are a top view thereof, it being understood that FIGS. 3A and 3B have been shown as separate figures for ease of illustration;

FIGS. 4A and 4B together are a bottom view thereof, it being understood that FIGS. 4A and 4B have been shown as separate figures for ease of illustration;

FIG. 5 is a left side view thereof;

FIG. 6 is a right side view thereof; and,

FIGS. 7A and 7B together are a front perspective view thereof, it being understood that FIGS. 7A and 7B have been shown as separate figures for ease of illustration.
